[57] CLAIM

The ornamental design for an illuminated electrical switch, as shown and described.

DESCRIPTION

FIG. 1 is a front, top, right side perspective view of an illuminated electrical switch showing my new design; FIG. 2 is a front elevational view thereof;

FIG. 3 is a right side elevational view thereof, the left side elevational view being a mirror image.

The bottom view of the switch housing is identical to the top view and the rear surface thereof is plain and unornamented.
